BLUE GAS SET

Reginald P. Oliveros, Williston Park, N. Y., assignor to Allied Chemical & Dye Corporation, New York, N. Y., a corporation of New York

Application January 29, 1949, Serial No. 73,469

3 Claims. (Cl. 48—82)

1

This invention relates to blue gas or uncarburated water gas sets.

Blue gas sets heretofore known commonly comprise a generator connected with an igniter which in turn communicates with a washbox. In operation the blue gas generated during the uprun passes through the igniter, the washbox and thence through the washer cooler and exhauster. In the operation of such sets with bituminous coal as the fuel in the generator, cracking or distillation of tar and volatiles carried by the make gas passing through the igniter takes place in the flow of this gas through the igniter with consequent formation of pitch, which interferes with the operation of the washbox, washer cooler and exhauster. For example, the pitch deposits in these units forming emulsions difficult to handle and producing deposits which must be removed for satisfactory operation. Further, blue gas sets heretofore employed have involved the use of valves, such as the well known hot valves, in the gas offtakes leading from the generator including the gas offtake connection between the generator and the igniter. These valves are in the path of flow of the high temperature make gases containing tar and other condensibles, which tend to deposit on the valve parts. The cost of these valves and the expense of maintaining them in reasonably clean operative condition increases materially the initial cost of the set and the expense of operating and maintaining the set in satisfactory condition.

It is an object of this invention to provide a simple, compact, efficient blue gas set free of the above noted objections to prior known blue gas equipment.

Other objects and advantages of this invention will be apparent from the following detailed description thereof.

In the accompanying drawing forming a part of this specification and showing for purposes of exemplification a preferred form of this invention without limiting the claimed invention to such illustrative instance,

Figure 1 is an elevational view of a blue gas set embodying this invention; and

Figure 2 is a plan view of the set shown in Figure 1.

The blue gas set of this invention comprises a generator 10, igniter 11 and washbox 12 connected as hereinbelow described. The igniter may communicate with a waste heat boiler (not shown), if desired.

The generator 10 has at its base a conical grate 13 provided with perforations in the surface

thereof and having its periphery 14 spaced from the inner side wall of the generator to form an annular opening 15. Disposed below the grate is a primary air inlet 16 through which air is admitted to the generator and uniformly distributed throughout the base of the fuel bed by means of the annular opening 15 and the perforations in the conical surface of the grate 13, which perforations are so spaced as to effect the desired uniform distribution of the air throughout the base of the fuel bed. A gas offtake 17 leads from below the grate and communicates with a backrun line 18 which leads into valve housing 19.

15   The generator is adapted to contain a bed of
fuel, desirably bituminous coal. The normal level
of this fuel bed is indicated by the reference
character 20. As the bituminous coal is con-
sumed in the water gas reaction fresh coal is
20 added through charging opening 21, which is
maintained closed, when the generator is not
being charged, by a suitable cover. If desired,
an automatic charging machine may be mounted
25 on the generator to charge bituminous coal
thereinto to maintain the coal level approxi-
mately constant at the height indicated by ref-
erence character 20. Leading from the top of
the generator above the level of the fuel bed is
a permanently unobstructed conduit 22 which
30 connects the top of the generator with the base
of the igniter 11. Conduit 22 leads into the
igniter tangentially to the circumferential body
portion thereof just above the conical base 23
of the igniter. In this way the gas stream en-
35 tering the igniter is given a swirling motion, ef-
fecting the removal of dust and other solid par-
ticles which settle into the conical bottom 23 from
which they can readily be removed, and minimiz-
ing deposition on the checkerbrick within the
40 igniter. Also leading from the top of the genera-
tor above the level 20 of the fuel bed therein is
a second conduit or uprun line 24. This uprun
line 24 is separate and independent from the
conduit 22 and leads into valve housing 19.

45 Valve housing 19 desirably is a substantially rectangular housing. The backrun line 18 and the uprun line 24 lead into ports in the side walls 25 and 26 of this housing. These two walls, as is evident from Figure 2, are at right angles to each other. A port in base 27 of this housing communicates through a pipe 28 with the washbox 12, which may be of any well known type, for example, a conical washbox as disclosed in Tweit Patent 2,373,519 granted April 10, 1945. A swing-
50 55 ing valve 29 is pivotally mounted in housing 19

and is arranged to be moved on its pivot so that it closes backrun line 18 and simultaneously opens the uprun line 24, and vice versa closes the latter line and places the backrun line 18 in communication with the valve housing 19.

The igniter 11 is a checkerbrick containing chamber of any desired type well known in this art. It is provided with a stack valve 30 through which the burning blast gases may be passed to the atmosphere. A connection 31 is disposed in a side wall of the igniter near the top thereof for connecting the igniter with a waste heat boiler when the latter is employed. If no waste heat boiler is used, connection 31 is sealed with a suitable closure plate.

A secondary air inlet 32 is provided in the unobstructed passageway 22 for supplying secondary air during the blasting step to support combustion of the blast gases which are burned during their flow through the igniter. A backrun steam inlet 33 leads into the top of the igniter and an uprun steam inlet 34 leads into the backrun pipe. By arranging the parts as shown in the drawing with the igniter disposed laterally to one side of and near the generator and the washbox positioned directly in back of and substantially between the generator and igniter, as shown in Figure 2, a substantial saving in piping is effected.

In operation the bed of bituminous coal in the generator 10 is first blasted with air admitted to the generator through 16, the resultant blast gases passing through conduit 22 mixed with secondary air admitted through 32 and the blast gases burned in their flow up through the igniter, exiting through stack valve 30, or, if a waste heat boiler is used, through outlet 31, thence into and through the waste heat boiler. During the blasting cycle the valve 29 is desirably positioned to close the uprun line 24. At the completion of the blasting step a short uprun is made, valve 29 being positioned to close the backrun line 18 and steam being supplied through inlet 34. This steam flows down through backrun line 18 and then up through the fuel bed, the resultant water gas passing through the uprun line 24 into the valve housing 19, thence to the washbox. A backrun step follows; valve 29 is positioned to close the uprun line 24 and place the backrun line 18 in communication with the valve housing 19. Steam is admitted through inlet 33 to the top of the igniter, flows down therethrough where it is superheated, then flows through the unobstructed passage 22 into and down through the fuel bed in generator 10, the resultant water gas being withdrawn through line 18 and flowing through valve housing 19 into washbox 12. At the completion of the backrun step, the main uprun follows. Steam is admitted through inlet 34 and valve 29 is positioned as hereinabove described in connection with the short uprun. The direction of flow of steam and water gas generated is the same as during the short uprun. Thereafter a short air purge may take place, air is admitted through 16 and the producer gas thus generated along with the water gas in the top of the generator flowing through the uprun line 24 into the washbox. This completes the cycle of steps and the cycle is thereafter repeated, the fuel bed being replenished as needed through the charging opening 21. If desired during the uprun steps, a small amount of steam may be admitted through steam inlet 33 and passed down through the igniter 11 into the top of the generator where it flows with the make gas through the uprun line 24 into the valve hous-

ing 19. In this way flow of make blue gas into the igniter 11 is prevented.

When employing a 4 minute cycle the duration of the steps of the cycle hereinabove described 5 may be divided as follows: blast 30%, short uprun 3% to 4%, backrun 55%, and main uprun 12% to 13%.

It will be noted that in the operation of the blue 10 gas set of this invention the blue gas generated does not pass through the igniter. Hence pitch formation due to cracking of tars and volatiles carried by the make gas flowing through the igniter, as in prior blue gas operation involving the use of bituminous coal as the fuel, does not take 15 place with consequent improvement in the operation of the washbox, washer cooler and exhauster. It will be further noted the blue gas set of this invention is simple and efficient in operation, compact in design and does not involve the use of any hot valves in the gas offtakes leading from the generator. Conduit 22 connecting the generator with the igniter is a permanently open and unobstructed passage free of valve or other gas flow 20 obstructing parts on which tar or other condensibles carried by the gas may deposit. Likewise the uprun and backrun lines are permanently unobstructed passages communicating with the valve housing 19 provided with a swinging valve which 25 can readily be cleaned.

30 Since different embodiments of the invention may be made without departing from the scope of this invention, it is intended that all matter contained in the above description or shown in the accompanying drawing shall be interpreted as 35 illustrative and not in a limiting sense.

What is claimed is:

1. A blue gas set consisting essentially of a generator having a grate therein, a single igniter, an unobstructed and valve free passageway connecting the top of the generator with the base of the igniter, a single washbox, a valve housing, a backrun line leading from the base of the generator to the valve housing, an uprun line separate and independent of said unobstructed and valve-free passageway leading from the top of the generator directly to said valve housing, a valve in said housing controlling flow through said backrun and uprun lines, and a conduit connecting said housing with said washbox.

2. A blue gas set consisting essentially of a single generator having a grate therein for supporting a bed of bituminous coal, a single igniter, an unobstructed and valve-free passageway connecting the top of the generator with the base of the igniter, a washbox, a valve housing, a backrun line leading from the portion of the generator below the grate to the valve housing, an uprun line separate and independent of said unobstructed and valve-free passageway leading from the portion of the generator above the normal level of the fuel bed therein directly to said valve housing, a valve in said housing for controlling flow through said backrun and uprun lines, a conduit connecting said housing with said washbox, an uprun steam inlet in the backrun line, and a backrun steam inlet at the top of the igniter.

3. A blue gas set consisting essentially of a single generator having a conical grate therein provided with perforations in the conical surface thereof for supporting a bed of bituminous coal, an igniter having a circumferential body portion and a conical base, an unobstructed and valve-free passageway connecting the top of the generator to the base of the igniter, the inlet of said passageway into said igniter being tangential to

said circumferential body portion and positioned just above said conical base, a washbox positioned between the generator and igniter, a valve housing disposed directly above said washbox, a backrun line leading from the portion of the generator below the grate into one wall of said valve housing, an uprun line separate and independent of said unobstructed and valve-free passageway leading from the portion of the generator above the normal level of the fuel bed therein directly to another wall of said valve housing at right angles to the first-mentioned wall, a pivoted valve in said housing controlling flow from said backrun and uprun lines into said valve housing, a conduit leading from the base of said housing into said washbox, a backrun steam inlet disposed at the top of the igniter, and an uprun steam inlet disposed in the backrun line.
